PUMP

Application filed July 9, 1928. Serial No. 291,236.

Our invention relates to improvements in water pumping devices of the general class shown in the co-pending application filed by Charles D. Cook, Serial No. 211,524, on 5 August 8, 1927. This type of pump comprises a long tubular conduit provided with a water inlet at its base and a water discharge at its top portion. This conduit is preferably formed of light material such as sheet 10 metal so as to provide a portable apparatus and this conduit, which is approximately eight or ten feet long, is provided at its upper portion with a relatively rigid support upon which is directly mounted a self-contained 15 prime mover preferably in the form of an outboard motor and in general comprising a two-cycle double opposed motor of two or more cylinders, an adjacently disposed gasoline tank, a combined rope starter, flywheel 20 magneto, a carburetor, a muffler, and other adjunctive devices whereby when the engine is started the prime mover may be continuously run for long periods of time without any connection to an outside source of fuel 25 or an outside source of power. The crank shaft of the motor is provided with an extension shaft passing downwardly through the long tubular conduit and at the bottom of the shaft is provided with a rotary impeller or 30 pump so that when operated, it will draw the water in through the lower portion of the tubular conduit, force it up through the tubular conduit, and discharge it from the outlet.

The objects of our present invention are to improve the constructional details of this general type of pump.

The improvements set forth in our present application include a novel means for circulating cooling water from the body of water contained in the longitudinal tube to the water jacket of the engine; the provision of automatic means for stopping the prime mover when the pump ceases to pump water 45 in any volume or an insufficient volume upwardly through the longitudinal tube; the various features of constructional assembly whereby an economical, simple, and light type of portable pump apparatus is provided.

These and other objects and the improved

features of our invention will be apparent from a perusal of the following specification when taken in connection with the accompanying drawings, wherein:

Figure 1 is a perspective view of our improved pump; 55

Figure 2 is a sectional side view of the lower portion thereof with parts broken away;

Figure 3 is a vertical section showing the 60 spiral arrangement of the water circulating tubes;

Figure 4 is a section taken on line 4—4 of Figure 2; and

Figure 5 is an enlarged cross sectional detail view of the automatic means for cutting out the spark in the gas engine when the water flowing through the longitudinal tube is insufficient or utterly fails. 65

Referring now to the drawings in detail, 70 our improved type of pump as shown in the illustrated embodiment, comprises a preferably cast iron base 2 provided with a threaded lower opening 4 adapted to detachably receive an extension foot if desired, and provided in addition with a plurality of angularly disposed webs 6 for strengthening the parts. The circular piece of the casting 2 is provided with any number of holes or perforations 8 constituting water inlet openings 80 for the base of the pump. This base 2 has detachably connected thereto as by means of screws 10 a preferably sheet metal casing 12 which encloses a circular metal casting 14 forming a frame or support for the pump proper and providing a pumping chamber. The pump proper comprises a hub portion 16 (see Figure 4) provided with a central aperture 18 adapted to receive the pump shaft hereinafter described. In addition, the pump is formed with a plurality of radially extending vanes 20 which are preferably slightly dished or curved as at 22 at their outer ends. These vanes 20 are of considerable height as shown clearly in side view in Figure 2 and they rotate about the central shaft and within a circular pumping chamber formed in the casting 14. This casting is provided with a plurality of vertically extending water deflecting blades 24 which curve from points 26 95 100

disposed close to the outer path of travel of the vanes 20 to points 28 preferably touching the inner wall of the sheet metal casing 12. These vanes form with the body of the casting 5 upwardly inclined and curved water deflecting portions 30, 32, 34, and 36 which at the high points 38, 40, 42, and 44 open in an upward direction into the chamber immediately above the pump rotor and connecting with the 10 main body of the long tube of the pump.

In order to better understand the construction and operation of the pump, it will be noted that as the pump is rotated by its shaft, the water will be drawn in through the inlet 15 openings 8 into the lower chamber 46 and from there will be drawn upwardly through the opening 50 (see Figure 4), which opening is substantially concentric with the axis of the pump hub and thence into the central portion 20 of the casting where this water will be thrown by the rotating blades 20 outwardly and thence up the curved inclines 30, 32, 34, and 36 and discharged out through the peripheral openings 38, 40, 42 and 44, which 25 communicate with the upper pump chamber 52.

The pump vanes 20 are, on their under sides, provided with upwardly inclined bottom edges 54 so as to sweep over an upwardly 30 inclined wall 56. We prefer to form this wall by means of two opposed sheet metal members 56 and 58 which converge in a wedge-like construction to a point 60 opposite a shoulder 62 on the bottom of the edges of the 35 vanes. In addition, the inner portions of the bottoms of the vanes are given a slight upward inclination to the central axis of the hub of the propeller. These two sheet metal portions are provided with laterally extending flanges 64 by which they are bolted by 40 means of screws 66 to the basal flange of the casting 14. This casting is likewise provided with a lateral threaded bore in which a screw 68 passes to hold the sheet metal casting 12 in position.

As shown clearly in Figure 2 of the drawings, the central hub 16 of the propeller is provided with a central vertical bore of three diameters. The upper diameter 70 receives 50 a cross pin 72 which passes through the shaft 74 hereinafter described. The diameter 76 of the hub 16 receives the lower end of the shaft 74 while the next smaller diameter 78 receives a screw or threaded bolt 80 having 55 a cap engaging the bottom portion of the hub 16 and this screw 80 threadingly engages the inner threaded bore 82 of the lower end of the shaft 74. By means of this construction, in order to disassemble the structure, it 60 is only necessary to unscrew the screw 80 and thence thread a slightly larger screw which fits the threaded opening 78 inwardly whereby the inner end of this next larger screw will 65 contact with the bottom end of the shaft 74 and will force it out. This makes a very

convenient way of removing the shaft 74 from the propeller.

Shaft 74 passes upwardly through a bearing 81 hereinafter described mounted on the upper portion of the casting 14 and thence passes upwardly to the top of the longitudinal conduit. This longitudinal conduit is preferably formed of sheet material so as to provide a light and portable structure. In general it is of slightly tapering formation as shown at 83 being fastened to the upper portion of the casing 12 by means of rivets or other suitable fastening means 84. This tapering tube 83 continues upwardly to its top where it is fastened by means of other rivets 86 to a motor casting 88 of rigid and sturdy construction. This casting is provided for one side with a water discharge outlet 90 in which we mount a sleeve 92 in the nature of an elbow and in addition is provided at its top with a very rigid cylinder block 94 which is rigidly mounted on an upper elbow 96. In addition the upper casting 88 is provided with an apertured pipe 98 substantially opposite the water discharge elbow 92 as herein-after described. The cylinder block 94 is provided with a central bearing 100 in which fits a depending drive shaft 102 from the engine 104 of the outboard motor and the upper portion of shaft 74 is adapted to make a detachable connection 106 with the engine shaft 102 so that when the outboard motor is unbolted from the engine block 94 it may be instantly removed by means of the splined clutch connection 106 with the extension shaft 74. While we are not restricted to the use of an outboard motor as being mounted on the engine block 94, we prefer this type of motor since it is light and portable in nature and is a self-contained power generating unit, not being dependent on any outside source for either electricity, fuel or other power generating medium such as a steam engine or an electric motor would be. As 100 is well known in the art, an outboard motor is of the type used in driving propellers of light water driven vehicles and comprises the usual gasoline tank 108, the rope-starter 110 and the combined flywheel and magneto 112 together with the usual muffler 114 and carburetor 116 and other adjunctive devices. Our invention contemplates the utilization of 105 part of the water which is pumped into the long tubular conduit 83 as a means for cooling the water jacket of the motor 112 of the power plant. To this end, we propose to conduct a portion of the water pumped into the conduit upwardly to the water jacket of the engine where it may be either discharged 110 outside of the tubular conduit 83 or may be recirculated back. In the present instance we prefer to provide a circulatory system whereby the water may be re-used. In the present instance, the engine block 94 is provided with two substantially vertical por- 115

tions 118 and 120 through which this cooling water may be conducted to and from the water jacket of the engine. These bores are provided with nipples 122 and 124 which connect pipes 126 and 128 respectively with the bores and hold the same in adjusted position. These pipes 126 and 128 extend in spiral formation as shown in Figure 3, longitudinally of the shaft 74 and the long conduit 83. The lower end of pipe 128 which is the water inlet pipe leading to the water jacket of the engine, terminates at a screen casing 130 surrounding a tubular casing 140 which in turn encloses and surrounds the 10
15 tension shaft 74. This casing 140 is of sheet metal and connects at its upper end to the cylinder block 94 being held in position thereat in any suitable manner. The lower end of this casing 140 is held to the upper portion 20
25 of the casting 14 by means of a metal ring 142 held in place by means of suitable screws 144. The screen 130 surrounding the inner casing 140 is open at its sides and preferably closed at its lower portion or bottom. 30
35 The water inlet pipe 128 communicates with the upper portion of the screen so that water taken into the screen passes into the pipe 128 and thence upwardly within the conducting tube 82 to the water jacket of the engine through which it circulates and is then conducted downwardly through the water inlet pipe 126 which preferably passes along on the outside of the screen 130 and discharges into the upper portion of the housing 142 on top of the casting 14. This upper portion of the casting 14 is somewhat hollowed out to form an upper chamber concentrically surrounding the lower portion of the shaft 74 and the lower portion of the chamber is 40
45 formed by means of a plate 146 screwed to the under surface of the casting 14 as at 148 and adapted to close the bottom portion of the chamber except for a relatively small opening 150 about the shaft 74. The central portion of the upstanding housing 142 on the casting 14 is threaded to receive a vertically disposed sleeve 152 which in turn is provided with a packed bearing 87 for the shaft 74. The opening 150 in the plate 146 50
55 forms a communication between the upper chamber 154 which communicates with the water discharge pipe 126 and the inner pump chamber and this communication is effected through the opening 150 of the plate and the largest bore 70 in the hub of the propeller and the upper or top portion of the propeller just beneath the plate 146. In other words, water in the chamber 154 passing down through the discharge pipe 126 will pass 60
65 through the opening 150 in plate 146 and thence will be forced outwardly by the rotating propelling vanes 20.

It will be noticed that this rotation of the main propeller 20 will create a substantial 65
vacuum or vortex at the hub 16 of the pro-

peller which will likewise cause a perceptible vacuum in the upper chamber 154 and this in turn will cause the water to be pulled through the pipe 120 and in the same manner cause the water to be sucked in through 70
75 the screen 130 from the interior of the conduct 83. Thus by the rotation of the propeller vanes 20 a positive circulation of water from the interior of the long pipe 83 is caused to flow through the screen 130 up the pipe 128 through the water jacket of the engine and back downwardly through pipe 126 into the chamber 154 and thence back into the main propeller chamber. 80

An advantageous feature of our present invention resides in the manner in which the conducting pipes 126 and 128 for the circulating water are spirally arranged in a longitudinal direction of the long pipe 83 and about the axis of the drive shaft 74. As the 85
propeller vanes 20 rotate and force the water up the circular inclines 30, 32, 34, and 36, the water is given an upward rotating or swirling motion and it is found that by arranging the pipes spirally substantially in the manner indicated, although any other spiral arrangement may be equally availed of, that the circulation of this water from the rotating blades through the pipes 126 and 128 is 90
95 greatly facilitated. 95

In our present invention, we provide means for controlling the prime mover as for instance by cutting out the ignition (although the fuel supply may be equally as well controlled) when the pump ceases to 100
105 force water upwardly through the long tubular conduit 83. Experience has shown that in cases where all the water is pumped up or in cases where the bottom of the pump becomes clogged with sand, sediment, or the like, the prime mover such as the gas engine might continue to function for long periods without having cooling water circulating through the water jacket and since this cooling water is taken from the pump as soon as delivered through the conduit 83, it is 110
115 necessary to provide some automatic means for controlling the engine. To this end we provide in the form illustrated, a diaphragm 156 which is shown in Figure 5 of the drawings, mounted in a sleeve 98 in the upper portion of the conduit and is clamped in position by means of a closing cap 158 provided with a bore at its outer end through which passes a stem 160 having a head 162. This stem in turn is provided intermediate its length with a threaded portion 164 to receive a collar 166 between which and the inner wall of the sleeve 158 the coiled compression spring 168 is forcing the rod 160 normally inwardly. The inner end of this rod is provided with clamping nuts which pass through the perforated diaphragm 156 and rigidly connect the rod 160 thereto. Directly in the path of collar 166, we provide a contact 120
125

member 170 mounted in an insulating bushing 172 and having an electrical connector 174 to the ignition circuit. This contact 170 forms a ground contact in the wellknown 5 ignition circuit so that when the metal collar 166 is in contact with the inner end of the contact 170 the ignition circuit is grounded and hence no spark will be created in the ignition chambers.

10 Since the electrical connections for such a circuit are wellknown to those skilled in the art, no details of such construction are given. The head 162 on the end of the rod 160 is slightly spaced in normal position as shown 15 at 176 so that when the head 162 is pulled out against the tension of the spring 168 a bifurcated clip 178 may be inserted between this head and the outer end of the sleeve 158 thereby to hold the metal collar 166 away from the 20 contact 170 so that the ignition circuit is closed to permit sparking in the cylinder. This clip 178 is mounted on a chain 180 permanently connected to the adjacent portion of sleeve 158 and in the position shown it is 25 most conveniently arranged so that when water is forced upwardly through the conduit 83 of the long tubular portion of the pump, this water will in normal operation press the diaphragm 156 outwardly thereby still further 30 pressing the rod 160 still further outwardly so as to permit the clip 178 to drop by gravity so that subsequently when the water ceases to be forced upwardly through conduit 83, the spring 168 will be permitted to force 35 the collar 166 to the right and contact the contact 170 thereby to ground the ignition circuit and stop the engine.

It will thus be appreciated that in our present invention we have provided a very simple 40 and practicable type of pump for removing the water from manholes, the holds of vessels or as a bilge pump, or for removing the water from excavations and the like and this pump is especially constructed to provide a light 45 portable device and wherein the long tubular conduit 83 is of sufficiently small diameter so that it may be inserted downwardly into relatively small manholes or the like to pump the water upwardly and discharge it outside of 50 the manhole. Another important advantage of our construction resides in the fact that although this pump is made of relatively light material such as sheet metal, the construction is such that the pump itself may 55 rest upon its sturdily constructed bottom such for instance as the bottom 4 and the web 6 and this bottom is arranged so that although standing upon it, it will not clog the inlet openings 8 so that water can freely pass into 60 the bottom portion of the pump and will be forced upwardly by means of the rotating propeller and discharged out through the upper elbow 92. Furthermore it will be 65 appreciated that in spite of the fact that we provide a very light portable pump, the con-

struction is such that the upper portion provides a very sturdy mounting or cylinder block on which a self-contained prime mover such for instance as an outboard motor, may be detachably mounted as by means of the 70 usual type of bolts which mount the prime movers of outboard motors on vertically depending shaft and propeller constructions.

Another advantageous feature of our present invention consists in the simple manner in 75 which a portion of the water is withdrawn from the longitudinal conduit 83 and passed to the water jacket of the engine and in fact recirculated through the jacket and this construction includes the spiral arrangement of 80 the circulating pipes which do not arrest or impede the upwardly swirling water delivered from the rotary pump. Furthermore by the arrangement of the inner tube 140 to enclose the longitudinal drive shaft 74, we 85 provide a concentric water passage longitudinally of the main casing 83 which confines the discharged column of water and insulates it from the central drive shaft 74 whereby the 90 bearings 81 and 100 for this shaft are 95 separated from the water being pumped. Furthermore by the provision of means for automatically controlling the gas engine or other prime mover and specifically by the means for cutting out the ignition circuit 100 when the supply of pumped water becomes 105 low or nil, we have provided means for preventing the overheating of the motor due to the fact that no circulating water can be 110 passed through its jacket.

While the pump as illustrated is adapted to have the entire weight of the pump rest upon the bottom 4, it will be appreciated that by a suitable attachment we may provide a 115 detachable tripod arrangement which will connect to the cylinder block or upper casting 96 so that the upper portion of the pump may be supported by this tripod. This of course is an ancillary support and is not necessary to the operation of our pump since the 120 main feature of the present type of pump consists of providing a long tubular conduit having a pump at its bottom and a prime mover at its top, the pump being constructed of light portable material but of sufficiently 125 sturdy construction that the entire weight of the pump may be born by the foot or bottom thereof.

Having thus described our invention what we claim as new and desire to secure by Letters Patent is:

1. In a pump of the character described, the combination of means forming a long tubular conduit and having a rigid base forming a pump support, a rotary pump mounted in said support, a water inlet for said pump, a water discharge at the upper end of said long tubular conduit, a cylinder block mounted in the upper portion of said long tubular conduit, a gas engine mounted 125

on said cylinder block connected to said pump and having a water jacket, said cylinder block having a water passage therethrough connected with the jacket, and a relatively small 5 pipe mounted wholly in said long tubular conduit terminating at its lower end in the conduit above the pump and connecting with the water passage in said cylinder block and suction means in connection with the suction 10 side of the pump for forcing water upwardly through said pipe to the water jacket of the engine.

2. In a device of the class described, the 15 combination of means forming a long tubular conduit and having a lower internal support and provided with a lower water inlet, a rotary pump mounted in said lower support, a cylinder block mounted on the upper end of said long tubular support, a gas 20 engine mounted on said cylinder block and having a drive shaft passing through said cylinder support and through said long tubular conduit and connecting with the pump, water passages formed through said cylinder block and connecting with the water 25 jacket of the engine, and water inlet and discharge pipes of relatively small diameter connecting with said passages and means for forcing water through said pipes to circulate 30 the same through the water jacket of the engine, said long tubular conduit having an upper water discharge.

3. In a device of the character described, 35 the combination of means forming a long tubular conduit having a water inlet at its base and a water discharge at its top, a lower support in said long tubular conduit forming a pump casing, a rotary pump in said casing, a cylinder block carried on the 40 upper portion of said long tubular conduit, a water jacketed gas engine mounted thereon, said gas engine having a shaft passing through said cylinder block through said long tubular conduit and connecting with the water pump and a sleeve connected to 45 the cylinder block and concentrically surrounding the drive shaft and connected to the lower pump casing and forming a concentric water passage whereby water forced 50 from the pump will be carried upwardly around said casing and discharged through the upper water outlet, and means for taking cooling water under pressure for the engine jacket from the concentric water passage and discharging it at the suction of the pump.

4. In a device of the character described, 55 the combination of means forming a long tubular conduit having a water inlet at its base and a water discharge at its top, a lower support in said long tubular conduit forming a pump casing, a rotary pump in said casing, a cylinder block carried on the upper portion of said long tubular conduit, 60 a gas engine mounted thereon, said gas en-

gine having a shaft passing through said cylinder block through said long tubular conduit and connecting with the water pump, and a sleeve connected to the cylinder block and concentrically surrounding the drive 70 shaft and connected to the lower pump casing and forming a concentric water passage whereby water forced from the pump will be carried upwardly around said casing and discharged through the upper water outlet, 75 water passages in said cylinder block connecting with the water jacket of the engine, and relatively small pipes connected to said water passages and extending longitudinally and within the long tubular conduit and outside of said casing concentrically surrounding the drive shaft, and pressure and suction means for circulating water through said pipes to and from the water jacket of the engine. 80

5. In a device of the class described, the combination of means forming a long tubular conduit provided with a water inlet at its base and a water discharge at its top, a water jacketed engine mounted on the top of said long tubular conduit and having a long drive shaft extending downwardly therethrough and provided with a rotary pump disposed at the bottom of said long tubular conduit for forcing water upwardly therethrough in a spiral path and discharging it through the upper outlet, and means for circulating a portion of the water in the long tubular conduit through the water jacket of the engine, said means including a spirally arranged pipe disposed in the path of the water within the long tubular conduit and extending longitudinally thereof. 95

6. In a device of the class described, 100 means forming a long tubular conduit provided with a water inlet at its bottom and a water discharge at its top, a water jacketed engine mounted at the top of said means and having a long drive shaft passing longitudinally thereof and provided with a rotary pump substantially at the bottom of the long tubular conduit, a casing concentrically surrounding said drive shaft and providing a concentrically surrounding water discharge passage, a sleeve-like screen carried by said sleeve and mounted adjacent the bottom portion of said long tubular conduit, a water inlet pipe having its inlet inside of said screen and connected with the water jacket of the engine, and a water discharge pipe connected with the discharge pipe of the water jacket of the engine and passing longitudinally within said long tubular casing, between said conduit and said sleeve surrounding the drive shaft, said discharge pipe terminating in a chamber connecting with the chamber in which the rotary pump rotates and substantially adjacent its central axis whereby to create a suction through said water discharge pipe when the pump rotates. 110 115 120 125

7. In a device of the class described, means forming a long tubular conduit provided with a water inlet at its base and a water discharge at its top, a water jacketed gas engine mounted at the top of said long tubular conduit and having a drive shaft passing longitudinally within said long tubular conduit and provided with a rotary pump located at the bottom of said long tubular conduit whereby water passing into the bottom of said long tubular conduit is pumped upwardly therethrough and discharged at the top thereof, a relatively small water circulating pipe opening within the long tubular conduit and connecting with the water jacket of the engine, and another pipe of relatively small diameter connecting with the discharge of the water jacket and said latter pipe connecting with the rotary pump casting at a point substantially adjacent its central axis whereby in rotation of said pump a suction is created through said discharge pipe.

8. In a device of the class described, the combination of means forming a long tubular conduit having a water inlet at its bottom and a water discharge at its top, a gas engine having a water jacket and mounted at the top of said long tubular conduit, said gas engine having a drive shaft passing longitudinally within said long tubular conduit and provided with a rotary pump mounted substantially at the bottom of said long tubular conduit, and suction means operated by and directly connected with the suction side of said pump for causing a circulation of water through the water jacket of the engine.

9. In a device of the class described, the combination of means forming a long tubular conduit having a water inlet at its bottom and a water discharge at its top, a gas engine having a water jacket and mounted at the top of said long tubular conduit above the water discharge, said gas engine having a drive shaft passing longitudinally within said long tubular conduit and provided with a rotary pump mounted substantially at the bottom of said long tubular conduit, and means operated by said pump for causing a circulation of water through the water jacket of the engine, said means being constructed and arranged to take a portion of the water forced by said pump upwardly through said long tubular conduit at a distance above the pump and pass the same through the water jacket of the engine and discharge it back into the long tubular conduit adjacent the bottom thereof and at the central suction side of the pump.

10. In a device of the class described, the combination of means forming a long tubular conduit having a water inlet at its bottom and a water discharge at its top, a gas engine having a water jacket and mounted

at the top of said long tubular conduit, said gas engine having a drive shaft passing longitudinally within said long tubular conduit and provided with a rotary pump mounted substantially at the bottom of said long tubular conduit, and pressure and suction means operated by said pump for causing a circulation of water through the water jacket of the engine, said means being constructed and arranged to take a portion of the water forced by said pump upwardly through said long tubular conduit at a distance above the pump but at the lower end of the conduit and pass the same through the water jacket of the engine and discharge it back into the long tubular conduit at the suction side of the pump, said circulating means being wholly mounted within the long tubular conduit.

11. In a device of the class described, the combination of means forming a water passage having an inlet and a discharge, a pump mounted therein for forcing water therethrough, a gas engine for operating said pump, a diaphragm mounted in the water passage, and a control device operated by the diaphragm for breaking the ignition circuit of the gas engine when the flow of water through the passage ceases and comprising a spring pressed contact stem with a head at the outer end, a sleeve through which the stem projects, and a clip insertable between the head and sleeve against the spring pressure for preventing a grounding of the ignition circuit until the fluid under pressure reaches the diaphragm.

12. An outboard motor pump comprising a long tubular conduit, a jacketed combustion engine at the top of the conduit, a rotary pump at the bottom of the conduit connected to the engine shaft, and means to cause a circulation of cooling water through the engine jacket comprising a pipe having an inlet in the conduit above the pump but adjacent the bottom of the conduit for receiving the pressure of the water pumped therein and a suction pipe extending from the jacket to the suction side of the pump whereby the engine will receive cooling water independent of the discharge of water from the conduit.

13. An outboard motor pump comprising a long tubular conduit, a jacketed combustion engine at the top of the conduit, a rotary pump at the bottom of the conduit connected to the engine shaft, and means to induce a flow of cooling water through the engine jacket comprising a water inlet above the pump in the lower end of the conduit, and a suction outlet adjacent the pump suction to raise water to the jacket in the inlet and withdraw water therefrom and discharging it through the pump.

14. An outboard motor pump comprising a long tubular conduit, a jacketed combustion engine at the top of the conduit, a rotary

- pump at the bottom of the conduit connected to the engine shaft, water inlet and discharge pipes in the conduit connected with the engine jacket, and means depending upon the
5 pump suction for forcing a portion of the water from the conduit through the pipes to circulate water through the engine jacket and back to the conduit through the pump itself.
- 10 15. A portable motor combustion pump comprising a long tubular conduit to stand uprightly, a pump at the bottom, and a fluid outlet at the top, a jacketed motor at the top of the conduit above the outlet, and means
15 for inducing a flow of cooling water through the motor comprising inlet and discharge pipes connected with the jacket and located in the conduit, the inlet pipe receiving the pressure of fluid from the pump adjacent the
20 bottom of the conduit, and the outlet pipe discharging adjacent the suction of the pump tending to withdraw the water therefrom.
- In witness whereof, I have hereunder subscribed my name.
